UNITED STATES PATENT OFFICE.

PETER C. McARDLE, OF CHICAGO, ILLINOIS.

CONCRETE-SURFACE-FINISHING MACHINE.

1,344,916.

Specification of Letters Patent. Patented June 29, 1920.

Application filed October 26, 1918. Serial No. 259,795.

To all whom it may concern:

Be it known that I, PETER C. McARDLE, a citizen of the United States, and a resident of the city of Chicago, in the county of Cook 5 and State of Illinois, have invented certain new and useful Improvements in Concrete-Surface-Finishing Machines; and I do hereby declare that the following is a full, clear, and exact description of the same, reference being had to the accompanying drawings, and to the numerals of reference marked thereon, which form a part of this specification.

This invention relates to an improved 15 form of a concrete finishing machine of simple and inexpensive construction, wherein a roller has finishing means associated therewith to afford a means whereby a concrete surface may be simultaneously rolled and finished.

It is an object of this invention to provide a device adapted to simultaneously roll and finish a concrete surface.

It is also an object of the invention to 25 equip a roller with a means adapted to finish a concrete surface as it is rolled.

Another object of this invention is the 30 construction of a machine adapted to simultaneously roll and finish the surface of a concrete surface as the machine is pushed or pulled thereover.

It is furthermore an object of this invention to construct a finishing machine wherein a float finisher is adapted to follow a 35 roller over a concrete surface to roll and finish the surface by the operation of the machine thereover.

It is an important object of the invention to provide a machine of simple and inexpensive 40 construction adapted to simultaneously roll and finish a concrete road or walk by pushing or pulling the machine thereover.

Other and further important objects of 45 the invention will be apparent from the disclosures in the drawings and specification.

The invention (in a preferred form) is illustrated in the drawings and hereinafter more fully described.

50 On the drawings:

Figure 1 is a side elevation of a rolling and finishing machine embodying the principles of this invention and showing the parts positioned to permit rolling and fin-

ishing of a concrete surface by pulling the machine thereover.

Fig. 2 is a top plan view thereof.

Fig. 3 is an enlarged detail section taken on line 3—3 of Fig. 1.

Fig. 4 is an enlarged fragmentary detail section taken on line 4—4 of Fig. 1.

As shown on the drawings:

The reference numeral 1, designates a heavy cylindrical roller or drum, made of metal or any other suitable material, and 65 rotatably journaled on an axle 2, which projects longitudinally therethrough and has the ends thereof transversely passaged. Centrally formed on each end of the roller 1, is a hub 3, to the outside of which a brace 70 or supporting arm 4, is disposed with one end thereof apertured and rotatably engaged on the axle 2. The other end of each of the arms 4, has an apertured flange 5, integrally formed thereon at an angle thereto, to permit retaining bolts 6, to be projected therethrough and into a long front float or finishing board 7, to securely hold said front finishing float secured to said arms 4, in a position parallel to the roller 1. 75

Disposed on each end of the axle 2, to the outside of the arms 4, is a washer 8.

Rotatably mounted on the axle 2, to the outside of the washers 8, are the inner parallel ends of handle tines or forks 9, which are 80 bent inwardly toward one another and have the outer ends thereof disposed parallel to each other and apertured to receive bolts 10, to rigidly hold said tines 9, secured on opposite sides of the lower end of a handle 90 11. Integrally formed or rigidly secured on the inner end of each of the tines 9, on the opposite side of the axle 2, from said tines is an inclined finger or lift 12, having a hook or projection 13, integrally formed 95 thereon, and projecting inwardly under the arm 4.

A washer 14, is engaged on each end of the axle 2, to the outside of the handle tines 9, to separate the same from the inner apertured ends of a pair of brace or supporting arms 15, one of which is rotatably engaged on each end of said axle 2. The outer ends of the arms 13, are bent at an angle to form flanges 16 which are apertured to permit 100 bolts 17, to project therethrough to rigidly hold a rear float or finishing board 18, in a position parallel to the roller 1. Rigidly

secured to the inner side of each of the arms 15, is the lower end of an upwardly directed hanger 19, the upper end of which is bent inwardly to afford a hook or catch 20, for a purpose hereinafter described. A retaining ring or washer 21, is disposed upon each end of the axle 2, and is held in position by a split pin 22, which projects through the passage provided for the purpose in the axle 2, 10 to hold the float arms, the handle tines and the washers in position.

The operation is as follows:

With the parts assembled as shown and described a simple and effective concrete surface rolling and finishing machine is produced which is adapted to be operated by means of a handle the upward and downward movement of which regulates or controls the relative positions of the finishing floats which form a part of the machine. When the machine is disposed upon a rough concrete surface, for example a concrete road or sidewalk, the machine may be pulled or pushed thereover to simultaneously roll 20 and finish the surface.

As shown in Fig. 1, the machine is positioned to permit the same to be pulled over a concrete surface in the direction of the full line arrow, in which position the handle 11, is in raised or elevated position, with the tines 9, thereof engaged under the hooks 20, of the hangers 19, thus holding the arms 15, and the rear float 18, in elevated position out of contact with the surface to 35 be finished. By elevating the handle 11, the lifts 12, are swung downwardly thereby moving the hooks 13, away from or out of engagement with the front float arms 4, permitting the front float 7, to drop by 40 gravity with the lower surface thereof resting on the concrete surface to be rolled and finished. The machine is then pulled by means of the handle 11, in the direction of the full line arrow, causing the drum 45 or roller 1, to roll and press the concrete thereby leveling the surface and at the same time acting as a tamping means to close up or fill any hollows or openings which may have formed in the concrete. The action 50 of the roller 1, also forces any excess moisture or water from the concrete and moves the same across the surface. As the roller is rolled over the surface the trailing float 7, resting by gravity upon the surface is 55 drawn over the leveled surface, and acts to smooth or finish the same. It will thus be noted that the machine simultaneously rolls and finishes a concrete surface.

When the opposite side of the surface 60 has been reached, and it is desired to go over the same portion of the surface or over an adjacent portion in an opposite direction as indicated by the dotted line arrow in Fig. 1, it is not necessary to reverse the machine as a unit. The novel

arrangement of the machine parts permits the handle and floats to be readily moved into the dotted line position of Fig. 1, by simply lowering the handle 11, thereby raising the lifts 12, the hooks 13, of which engage beneath the float arms 4, and raise the same and the float 7, out of engagement with the concrete surface. With the lowering of the handle the float 18, simultaneously drops by gravity into contact with 75 the concrete surface, in which position the hooks 20, of the hangers 19, are of course out of engagement with the handle tines 9. The machine is then pushed over the surface and acts to simultaneously roll, tamp 80 and finish the surface as already described.

It will of course be understood that the machine is shown in a very simple form to permit the same to be constructed at a low first cost and of a size to afford convenient 85 operation transversely or longitudinally over a concrete surface by a single operator. The machine may be built in different sizes, and the parts may be constructed in a number of different ways to provide, a 90 rolling and finishing machine. When desired the front float 7, may be swung upwardly around the axle 2, into a position out of use, resting upon the handle forks 9, or the handle may be thrown to the opposite side of the roller 1, in which position the rear float 18, rests upon the handle forks 9. The float members may also be arranged to be moved into and out of operating position by means other than those 95 shown.

I am aware that numerous other details of construction may be varied through a wide range without departing from the principles of this invention, and I therefore 105 do not purpose limiting the patent granted otherwise than necessitated by the prior art.

I claim as my invention:

1. A rolling and finishing device, comprising a roller mechanism, an axle projecting therethrough, finishing mechanisms connected therewith, and means on said axle and engaging said finishing mechanisms for simultaneously moving said roller and adjusting said finishing mechanisms. 110

2. In a device of the class described, the combination with a roller mechanism, finishing means adjustably connected therewith, means for holding said finishing means in a position out of use, and a handle secured 120 to said means for moving said roller mechanism, said handle adapted to be adjusted to permit said means to be lowered into a position for use.

3. In a device of the class described, the combination with a surface leveling roller mechanism, finishing means adjustably connected therewith and disposed on opposite sides thereof, and handle means connected with said mechanism and means for simul- 125 130

taneously actuating the same, said handle means adapted to be raised or lowered to move said finishing means out of and into operating position independently of said 5 roller mechanism.

4. A machine of the class described comprising a roller, a plurality of smoothing members on opposite sides of said roller and pivotally connected therewith, and a handle 10 connected with said roller and with said members, said handle adapted to be operated to raise one of said members into a position out of use and lower the other member into a position for use to finish a concrete 15 surface as it is leveled by said roller.
5. A rolling and finishing device com-

prising roller means, finishing members connected therewith, means for simultaneously actuating said roller and finishing members, and means connected with said actuating 20 means, for moving one of said finishing members out of operating position as the other finishing member is moved into a finishing position.

In testimony whereof I have hereunto 25 subscribed my name in the presence of two subscribing witnesses.

PETER C. McARDLE.
